UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed March 22, 1923. Serial No. 626,825.

To all whom it may concern:

Be it known that I, EPPA H. RYON, a citizen of the United States, residing at Waltham, in the county of Middlesex and State of Massachusetts, have invented a new and useful Weft-Detecting Mechanism, of which the following is a specification.

This invention relates to a detecting mechanism for a weft replenishing loom and is designed to indicate substantial or 10 complete exhaustion of weft on the active weft carrier in a reliable and effective manner.

It is an important object of my invention 15 to provide a weft replenishing mechanism so designed that the portion of the loom stopping or indicating mechanism which is engaged by the weft detecting member may have an operative movement in a direction 20 substantially at right angles to the movement of said detecting member while maintaining operative relations therewith in all positions thereof. A further object of my invention is to provide a convenient means 25 by which the effective length of the weft detecting member may be conveniently adjusted and maintained.

To the attainment of these objects in 30 their preferred embodiment, I provide a two-piece detecting member movable in a substantially horizontal direction and an arm or latch continuously positioned thereby but movable by an actuating device in a substantially vertical direction.

35 My invention further relates to arrangements and combinations of parts which will be hereinafter described and more particularly pointed out in the appended claims.

40 A preferred form of my invention is shown in the drawings, in which

Fig. 1 is a side elevation of my improved detecting mechanism;

Fig. 2 is a plan view thereof;

45 Fig. 3 is a sectional side elevation taken along the line 3—3 in Fig. 2;

Fig. 4 is a partial sectional rear elevation, taken along the line 4—4 in Fig. 1, and

50 Fig. 5 is a detail sectional elevation, taken along the line 5—5 in Fig. 3.

Referring to the drawings, I have shown a portion of a loom side 10 on which is mounted a stand or bracket 11 supporting

a pivot 12 for an arm 13. The arm 13 is 55 connected by a link 14 with an arm 15 on a shaft 16 extending across the front of the loom and connected to suitable and usual mechanism for stopping the loom or for indicating a weft carrier transfer as may be 60 desired.

A lever 17 is mounted on a stud 18 extending from the side of the arm 13 at a point intermediate its ends and a weight 19 on the lever 17 normally maintains the lever 65 in the position shown in full lines in Figs. 1 and 3. An actuator 20 is mounted for vertical reciprocation in a bearing 21 by driving mechanism not shown, and is provided with a notch or recess 22 adapted to 70 receive the pointed lower end of an arm 23 integral with the lever 17 and weight 19. By such engagement the lever is forced upward and moves the shaft 16 angularly 75 through the arm 13, the link 14 and the arm 15. The normal position of the arm 13 is determined by a stop screw 24 adjustably threaded in a portion of the bracket 11.

The weft detecting member 26 is preferably formed with a cylindrical body 80 slidable in a horizontal passage 27 in the stand 11. The weft engaging portion of said member is of substantially rectangular cross section, as indicated in Fig. 5, and this part of the detector is held from angular movement by a stop plate 28 having a screw 85 and slot adjustment on the stand 11 and having a non-circular opening through which the rectangular part of the detector is 90 slideable.

A head 30 is threaded to the detecting member and has a flattened portion fitting within a longitudinal groove 31 in the lever 17. The length of the detecting member may be readily adjusted by manually moving the 95 lever to the dotted line position in Fig. 3, and thereafter turning the head 30 on the thread of the detecting member, thus shortening or lengthening the member as desired.

When the lever 17 is released, the flattened 100 end of the head will be received in the groove 31 and will be held from angular movement thereby.

The normal position of the parts is shown in Fig. 1 with the lever 17 in the path of 105 the actuator 20. If the detecting member engages a sufficient supply of weft on the active weft carrier, it will be pushed for-

ward by the lay, swinging the lever 17 out of the path of the actuator as the lay beats up. When, however, the weft becomes substantially or entirely exhausted, the detector 5 will permit the lever to remain in its normal position, with the arm 23 in the path of the actuator, whereupon the arm and lever will be pushed upward thereby and will operate through the arm 13 to rock the shaft 16 and stop the loom or replenish the weft supply.

It will be noted, that in every vertical position of the lever 17, the head 30 of the detecting member 26 remains in the groove 15 31 and the operative relation of the parts is thus maintained. The detecting member shown in the drawings is particularly adapted for use with a bobbin having a slot into which the detector enters when the weft 20 is exhausted, but it will be understood that my invention is not limited to use with this type of bobbin nor with this particular detecting member except as set forth in the claims.

25 What I claim is:—

1. A detecting mechanism for a weft replenishing loom comprising a detecting member movable forward with the lay when engaged by a weft carrier having a sufficient supply of weft thereon, an actuator 30 movable transversely to the path of movement of said detecting member, an arm mounted on a fixed pivot, a lever pivoted on said arm and normally depending adjacent 35 said detecting member, and connections through which said arm and lever are moved transversely to said detecting member by said actuator upon weft exhaustion, said de-

tecting member and said lever having portions cooperating with each other in every 40 transverse relation thereof.

2. In a weft replenishing loom, a swinging lever having a longitudinal groove therein, means to move said lever lengthwise of said groove, and a weft detecting member having a non-circular end fitting said groove and engaging said lever in every operative 45 position thereof.

3. In a weft replenishing loom, a two-piece weft detecting member, one portion 50 thereof being slidably but non-rotatably mounted and engaging the weft on the active weft carrier, and the second portion thereof being slidably and rotatably mounted and having a threaded connection to said first 55 portion, said second portion having a non-circular end, and a grooved lever pivoted above said detecting member and receiving the non-circular end thereof in said groove, whereby relative rotation of the parts of 60 said detecting member is prevented.

4. In a loom, a stand, a weft detecting member, and a device engaged thereby, said member being formed in two parts having a threaded connection by which the length 65 of said member may be adjusted, one of said parts being held from angular movement by said stand and the other part being held from angular movement by engagement with said device, and means to move said device 70 transversely relatively to said member while preserving the operative relation between said member and device.

In testimony whereof I have hereunto affixed my signature.

EPPA H. RYON.
